UNITED STATES PATENT OFFICE.

EMIL TYDEN, OF EVANSTON, ILLINOIS.

VALVE-SEAT CUTTER.

Application filed May 21, 1923. Serial No. 640,358.

The purpose of this invention is to provide a tool for machining a surface such as a valve seat, which is not directly accessible but must be reached through an opening in the part such as a bore through the valve seat surface. The invention consists in certain features and elements in combination as herein shown and described and as indicated by the claims.

10 In the drawings:

Figure 1 is a side elevation of a tool embodying this invention showing it entered in a piece of work with the parts adjusted for such entry.

15 Figure 2 is a plan view of the tool with the work turned at 90 degrees to the position shown in Fig. 1 and with the tool adjusted to cutting position.

20 Figure 3 is an enlarged view of the cutter and its supporting stem adjusted as shown in Fig. 1.

Figure 4 is an enlarged view of the cutter and its supporting stem adjusted as in Fig. 2.

25 Figure 5 is an end elevation of the tool with the range of adjustment indicated in dotted lines.

For purposes of illustration, the piece of work shown in connection with the tool is a 30 sprinkler head for an automatic sprinkling system in which a frame, 1, extends from the threaded stem, 2, at opposite sides of the bore, 3, in said stem. The bore, 3, terminates within the outlines of the frame, 1, in an annular valve seat, 4, opposite which the frame is arched at 5 to carry a boss or abutment, 6, which is located coaxially with the bore, 3, and therefore obstructs access to the seat, 4, for machining it in the ordinary manner. The purpose of this invention is to 40 provide a tool which may be entered through the bore, 3, and adjusted to work upon the valve seat, 4, and then re-adjusted for withdrawal through the said bore, 3.

45 It may be assumed that the frame, 1, is carried in a special chuck, 7, by which it is rotated in a lathe or similar machine; the drawing shows only one of two jaws of such a chuck, the other jaw being omitted to 50 close the outlines of the sprinkler head and to show the recess, 8, formed in the jaw to accommodate the part, 6, of the casting. The turret head or other tool support is mounted opposite the chuck, 7, and the tool 55 carried thereby includes a stem, 10, fitted to enter the bore, 3, and slightly reduced at its

end portion, 11. A rock shaft, 12, is eccentrically carried in the stem 10, and supports at its outer end a head, 13, which, at one position of adjustment of the rock shaft, 12, 60 is co-axial with the stem, 10, and substantially equal in diameter to the reduced portion, 11. The head, 13, is bored in a direction at an acute angle to the longitudinal dimension of the rock shaft, trending from 65 the end thereof rearward, i. e., toward the shank to receive the cutter, 14, of tool-steel which may be secured in position by a set screw, 15, in the head. The end of the reduced part, 11, of the stem, 10, is notched 70 at, 11^a, to accommodate the cutter, 14, as indicated clearly in Figure 3, so that when the head, 13, is adjusted to its concentric position, the cutter lies wholly within the 75 outlines of said head and the stem and it may be readily entered through the bore, 3, to the position shown in Figure 1.

The main shank, 16, of the tool is held fixed in the turret or other support on the machine; between said shank and the stem 80 10, there is formed a flange or enlargement, 17, having a slot, 18, which accommodates the swing of an adjusting handle, 19, which is fixed to the inner end of the rock shaft, 12, by a suitable set screw, 20. The adjustment of the rock shaft is very simply accomplished, by swinging the arm or handle 85 19, from the position shown in full lines in Fig. 5 to the position shown in dotted lines in said figure, whereby the rock shaft, 12, 90 and its head, 13, are rotated through an angle of about 90 degrees carrying the cutter, 14, outside the projected outlines of the stem, 10, and in position for encounter with the surface of the valve seat, 4, when the 95 tool is drawn back slightly in the bore, 3. As the part, 1, is revolved by the chuck the cutter, 14, being adjusted to the position shown in Figure 2, works upon the valve seat for shaping and smoothing it and upon completion of this operation,—the tool being advanced away from the machined surface,—the cutter is returned to its original position by the swing of the adjusting handle, 19, and the tool is withdrawn through the 100 bore, 3. The swing of the head, 13, may be limited in one direction by the engagement of the cutter, 14, with one side of the notch, 11^a, and in the other direction by encounter of the arm, 19, with the wall, 21, of the slot, 18; for convenience, this wall, 21, is cut 110 straight through the flange, 17, but if it be

preferred to prevent the cutter, 14, from actually engaging the end of the notch, 11^a, the slot, 18, may be formed with a second wall, 22, as indicated in Fig. 5, for limiting the adjustment by encounter with the handle, 19.

I claim:

1. A tool for the purpose indicated comprising a stem, a cutter holder mounted at the forward end thereof, and a blade fixed in the holder and provided with a cutting edge at its free extremity, said blade projecting from the rear face of the holder but lying entirely within the projected outline of the holder, and said holder being adjustable with respect to the stem for shifting the cutting edge of the blade laterally beyond the projected outline of the stem for operating upon a forwardly facing area of a piece of work through which the stem is protruded.

2. A tool of the character described in claim 1, wherein the cutter holder is eccentrically mounted within the stem, and rotatable with respect thereto, for the purpose of shifting the cutter blade laterally as described.

3. A tool for the purpose indicated comprising a stem, a rock shaft eccentrically journaled therein, a cutter holder on the end of the rock shaft beyond the stem, dimensioned to lie within the projected outline of the stem at one position of adjustment, said holder having an obliquely disposed bore piercing the rear face thereof, means for securing a cutting blade within the bore, adjustable in the oblique direction of said bore to project therefrom rearwardly but lying

within the projected outline of the holder, said blade being provided with a cutting edge at its free extremity, and means to rock the shaft to swing the holder laterally to expose the cutter blade in working position.

4. A tool for the purpose indicated comprising a stem with a supporting shank, a rock shaft eccentrically journaled in the stem and extending into the shank, a cutter holder fixed on the rock shaft at the forward end of said stem, and a cutter in the holder adapted to be extended laterally into working position by turning the rock shaft, the shank having a transverse slot into which the rock shaft extends and a handle snugly fitting said slot and rigidly secured to the rock shaft for turning the latter while retaining it against longitudinal movement.

5. A tool for the purpose indicated comprising a stem, a cutter holder rotatably mounted therein at one end thereof, said holder having an obliquely disposed bore piercing its rear face for receiving a cutter blade, means for securing a blade therein with its cutting edge lying within the projected outline of the holder, said holder being dimensioned for lying within the projected outline of the stem at one position of its rotative adjustment, and for carrying the cutter outside said outline at another position of adjustment.

In testimony whereof, I have hereunto set my hand at Chicago, Illinois this 18th day of May, 1923.

EMIL TYDEN.
